UNITED STATES PATENT OFFICE.

FRANK A. MILLER, OF CINCINNATI, OHIO.

IMPROVEMENT IN CAR-HEATING APPARATUS.

Specification forming part of Letters Patent No. **178,178**, dated May 30, 1876; application filed April 28, 1876.

To all whom it may concern:

Be it known that I, FRANK A. MILLER, of Cincinnati, Hamilton county, Ohio, have invented a new and useful Car-Heating Apparatus, of which the following is a specification:

In the accompanying drawings, Figure 1 is a partially-sectioned elevation of an apparatus embodying my invention. Fig. 2 is a plan of a car-floor furnished with steam-heated pipes. Fig. 3 is a perspective representation of my mode of coupling the pipes. Fig. 4 is an enlarged section of my thimble-coupling.

A and A' represent portions of the floors of two consecutive cars. B B' are pipes which receive steam from the engine or from any generator. C are drip-cocks. D are stop-cocks. 1 2 3 1' 2' 3' are short pipes or tubular sections, which communicate by thimble-connections E, which, while permitting free steam communication from section to section, yet

allow any section to sway to the right or left in conformity with the oscillations of the train. The two terminal sections 3 and 3' are of such relative caliber as for one to fit within the other, and be secured thereto by claws or hooks F, which, being passed through openings g, engage behind shoulders or flanges G, one section being for that purpose partially rotated upon the other.

I claim as new and of my invention—

The two series of jointed steam-pipes 1 2 3 and 1' 2' 3', with thimble-connections E and the coupling F G g, as and for the purpose set forth.

In testimony of which invention I hereunto set my hand.

FRANK A. MILLER.
